UNITED STATES PATENT OFFICE.

MAURICE B. LONG, OF GLEN RIDGE, NEW JERSEY, ASSIGNOR TO WESTERN ELECTRIC COMPANY, INCORPORATED, OF NEW YORK, N. Y., A CORPORATION OF NEW YORK.

TRANSMISSION OF PICTURES BY ELECTRICITY.

Application filed August 14, 1924. Serial No. 731,946.

To all whom it may concern:

Be it known that I, MAURICE B. LONG, a citizen of the United States, residing at Glen Ridge, in the county of Essex, State of New Jersey, have invented certain new and useful Improvements in Transmission of Pictures by Electricity, of which the following is a full, clear, concise, and exact description.

10 This invention relates to a system for the transmission of pictures by electricity and more particularly to reproducing equipment for such a system.

It was known prior to this invention that 15 pictures could be transmitted from one place to another by means of electric currents, some characteristic of which was varied in accordance with the tone values of successive elemental areas of the picture. In a 20 common form of equipment, the amplitude of the current is varied at the sending terminal, which varying current is employed at the reproducing terminal to actuate the reproducing equipment.

25 An object of the present invention is to increase the flexibility of the reproducing equipment.

Another object is to effect the reproduction 30 as either a positive or negative of the original picture, independently of the sending terminal.

In one embodiment of the invention, the tone values of the elemental areas of the picture to be transmitted are sent as modulations of a voice frequency carrier wave. 35 At the reproducing terminal, this wave is demodulated in a three-electrode electron discharge device, the demodulated current being used to operate an electromagnetic 40 light valve for controlling the exposure of a light sensitive record blank. A biasing battery and switch are connected into the light valve circuit in such a way that by throwing the switch from one of its two 45 circuit closing positions to the other, the reproduced picture may be changed from a negative to a positive of the original or vice versa. In another embodiment employing a similar battery and switch, the modulated 50 carrier wave is impressed directly upon the light valve which functions as a demodulator.

The novel features which are considered 55 characteristic of this invention are set forth with particularity in the appended claims.

The invention, both as to its organization and method of operation together with other objects and advantages thereof, will be further explained in the following description having reference to the accompanying drawing.

Fig. 1 of the drawing is a schematic diagram of a system in which an electron discharge device functions as the demodulator.

Fig. 2 is a diagram which will be used in explanation of the operation of the system of Fig. 1.

Fig. 3 is a schematic diagram of the reproducing equipment wherein the light valve functions as the demodulator.

Figs. 4 and 5 show the relative positions of the light valve strings for different conditions, the elements being greatly enlarged.

Referring now to Fig. 1 rotatable drums 5 and 6 are mounted on shafts 7 and 8 which are caused to rotate in any suitable manner. 75 As the drums rotate, they are caused to move axially with respect to the shafts. Upon the drum 5, there is mounted a transparency 9 of the picture which is to be transmitted. Mounted upon the drum 6 is a record blank 10, such as a sensitive photographic paper or film. Located within the drum 5 and transparency 9 is a photo-electric cell 11, the electrical characteristic of which is affected 80 by the amount of light received from a source 12, through a lens 13 which projects an image of the light source 12 upon the transparency 9 of the picture. The amount of light reaching the photo-electric cell 11 85 is determined by the tone value of the elemental area of the transparency 9 which is opposite the focal point of lens 13 at any given time.

The terminals of the photo-electric cell 11, 90 are connected to a modulating device 14, whereby carrier waves from a source 15 are modulated and transmitted to the transmission line L. At the reproducing terminal, carrier waves from the line L are impressed 95 upon a demodulator D after amplification in an amplifier 16. The modulating device 14, amplifier 16 and demodulator D may each consist of three electrode electron discharge devices as indicated. A suitable arrangement for synchronously rotating the drums 5 and 6 and modulating and amplifying the carrier waves in accordance with picture currents from the photo-electric cell 11, 100 is disclosed in applicant's copending appli- 105

cation, Serial No. 681,347, filed December 18, 1923.

The movable conductors 17 and 18 of a light valve V are connected to the output circuit of demodulator D. The light valve V controls the amount of light which may pass from a source 19 to effect exposure of the light sensitive record blank 10. The light valve V is similar in general arrangement to the light valve disclosed in a pending application of E. C. Wente, Serial No. 635,886, filed May 1, 1923. The movable conductors or strings 17 and 18 are suspended in a magnetic field which is produced by a winding 20. A portion of the strings 17 and 18 are intensely illuminated by light from source 19 passing through lens 21 and an image of the aperture formed by strings 17 and 18 is projected upon the film 10 by means of the lens 22.

In order that either a positive or a negative of the transparency 9 may be reproduced on the film 10, independently of the received current from line L, a switching circuit is provided in the output circuit of demodulator D. This circuit comprises a series circuit including battery 23, switch 24 and strings 17 and 18, connected across resistance 25, which resistance is connected in series with battery 26. An ammeter 27 is provided to indicate the amount and direction of the current flowing through the light valve.

Battery 23 is of such a value that for a given light condition in the photo-electric cell 11, the valve V is closed with the switch 24 in one position, and opened with the switch 24 in its other position. For example, assume the dark condition of the photo-electric cell 11 which corresponds to an opaque elemental area of the picture to be transmitted. If the light valve is wide open, the reproduced picture will be a positive of the original; while if the light valve is closed under this condition, the reproduced picture will be a negative of the original.

The positions of the strings 17 and 18 for these two conditions are illustrated in Figs. 4 and 5. In Fig. 4, the strings 17 and 18 are shown fully opened with respect to an aperture 28 in the light passage of the light valve. In Fig. 5 the strings are fully closed.

In Fig. 2 there is illustrated a curve showing the relation between the rectified picture current and the current through the light valve. When the current through the light valve has the value OA, the valve is so adjusted as to be completely open. As the picture current increases in accordance with successively darker elements of the picture, the light valve current also increases in the positive direction, resulting in a corresponding closure of the valve. Under these conditions a negative reproduction is obtained.

The converse is true when switch 24 is operated to the left, when battery 23 tends to maintain the valve closed and incoming picture currents tend to open the valve, resulting in a positive reproduction.

Referring now to Fig. 3, the modulated carrier waves from the line L are amplified in amplifier 16 and impressed directly upon the strings 17 and 18 of light valve V by means of transformer 30. The reproducing drum and optical system is the same as in Fig. 1, like reference characters being used to designate like elements in the two figures.

In order to provide for changing the reproduction from a negative to a positive or vice versa, battery 31 together with switch 24 is connected across a resistance 32, the resistance 32 being connected in series with the strings 17 and 18. The value of the current flowing in strings 17 and 18 due to the potential drop across the resistance 32 is determined by rheostat 33. Changing switch 24 from one operating position to the other, changes the polarity of the potential drop through resistance 32, and hence the direction of the current flow in strings 17 and 18. The value of the direct current component of the current flowing in strings 17 and 18 is adjusted by means of rheostat 33 so that, when no carrier current is superimposed thereon from the amplifier 16, the aperture formed between strings 17 and 18 is either open or closed, depending upon the position of switch 24. Assume that the dark condition at the photo-electric cell produces carrier current of maximum amplitude, that the valve tends to close when positive potential is impressed upon the string 18 and that the switch 24 is in the position shown to close the valve. The valve will therefore be opened as each negative impulse of maximum carrier current is received and a positive reproduction will result. With the switch 24 thrown in its left hand position, the valve will be closed when the maximum carrier current is received and a negative reproduction will result.

From the foregoing, it is clear that with either of the arrangements of Fig. 1 or Fig. 3, the type of reproduction such as a negative or a positive may be changed by changing the position of switch 24. The type of reproduction is therefore independent of the current transmitted from the sending terminal and the flexibility of the equipment is greatly increased. It is obvious that sometimes it may be more desirable to have the reproduction in the form of a negative. At other times a positive may be the preferable form. By the arrangement of this invention, either type may be obtained independently of the sending terminal.

It is not necessary that the picture current from the photo-electric cell 11 be transmitted as modulations of a carrier wave but it

may be transmitted directly to the light valve V with or without amplification as the requirements of the circuit demand. The scope of the invention is not to be limited by the specific embodiments shown in the drawing but only by the appended claims.

What is claimed is:

1. In a system for the transmission of pictures by electricity, means to produce picture currents, means including an electro-magnetic light valve for reproducing the picture, and means to change the type of the reproduced picture from a positive to a negative or vice versa.

2. In a system for the transmission of pictures by electricity, means to produce picture currents, means including an electro-magnetic light valve for reproducing the picture, and means connected in circuit with said light valve to change the type of the reproduced picture from a positive to a negative or vice versa.

3. In a system for the transmission of pictures by electricity, means to produce picture currents, an optical arrangement including an electro-magnetic light valve for reproducing the picture, a three electrode electron discharge device controlled by said picture currents to operate said light valve, and means connected in the output circuit of said discharge device to change the type of the reproduced picture from a positive to a negative or vice versa.

35 4. In a system for the transmission of pictures by electricity, means to produce picture currents, an optical arrangement including an electro-magnetic light valve for reproducing the picture, a three electrode electron discharge device controlled by said picture currents to operate said light valve, a biasing battery connected in series with said light valve, and a reversing switch for interchanging the electrical conditions of 45 the terminals of said light valve whereby the type of the reproduced picture may be changed from a positive to a negative or vice versa.

5. In a system for the transmission of pictures by electricity, means to produce picture currents, means to modulate a carrier wave in accordance with said picture currents, a three electrode electron discharge demodulator for demodulating said modulated wave, an output circuit for said demodulator, a resistance connected in said output circuit, an electro-magnetic light valve connected across said resistance, a bat-

tery connected in series with said light valve, and a reversing switch connected between said battery and said light valve for reversing the electrical conditions of the terminals of the valve.

6. In a system for the transmission of pictures by electricity, means for producing picture currents, means including a light valve for reproducing a picture, a space discharge device controlled by said currents for operating said valve, and means in the output circuit of said device for changing the type of the reproduced picture from a positive to a negative or from a negative to a positive.

7. In a system for the transmission of pictures by electricity, means for producing picture currents, means including a light valve for translating said currents into corresponding picture characteristics, means comprising a battery and a switch in circuit with said valve for normally maintaining said valve either open or closed, and means controlled by said picture currents cooperating with said battery to correspondingly vary the open or closed condition of said valve.

8. In a system for the transmission of pictures by electricity, means for producing picture currents, an arrangement including a light valve for reproducing the picture as a negative or as a positive, a space discharge device controlled by said picture currents to operate said valve, a biasing battery connected in circuit with said valve adapted to normally maintain said valve open or closed, and a switch cooperating with said battery to determine the positive or negative type of the reproduced picture.

9. In a system for the transmission of pictures by electricity, means for producing picture currents, means including a light valve for translating said currents into corresponding picture characteristics, a biasing battery adapted to maintain said valve completely open when an opaque characteristic of a picture is to be transmitted, means for allowing said battery to maintain said valve completely closed when an opaque characteristic of said picture is to be transmitted, and means controlled by the varying characteristics of the picture to be transmitted for correspondingly varying the control of said biasing battery over the open or closed condition of said valve.

In witness whereof, I hereunto subscribe my name this 7th day of August A. D., 1924.

MAURICE B. LONG.
